ATTACHMENT FOR SEWING MACHINES

Charles Seaman, Jamaica Estates, N. Y.

Application April 6, 1943, Serial No. 481,972

23 Claims. (Cl. 112—214)

This invention relates to sewing machines and to an attachment therefor. More particularly, this invention relates to a sewing machine and attachment for preventing the accumulation of the material on the work support after the sewing operation, particularly when two pieces of relatively wide material are joined by a seam and the two pieces of material extend on opposite sides of the seam.

Prior to this invention, when two pieces of relatively wide material were joined together by a seam formed by a sewing machine and the two pieces of material extended from the seam in opposite directions, the seamed material accumulated or collected on the work support beyond the needles. Depending on the relative widths of the material joined together, portions thereof collected on the work support in the vicinity of or beyond the needles and to the right or to the left, or both to the left and right, of the needles. Due to this, the operator frequently had to interrupt and stop the sewing operation and remove the accumulations.

An object of this invention is a sewing machine provided with means to cooperate with the work support to remove the material after the sewing operation and prevent accumulation on the work support of the material subjected to the sewing operation.

Another object of this invention is a sewing machine attachment which is adapted to be quickly mounted on a sewing machine without in any way mutilating the same and which will cooperate with the work support to continuously feed the material after the sewing operation has been performed and prevent accumulations thereof on the work support.

Other and additional objects will become apparent from the full and complete description of the invention hereinafter set forth.

In general, the objects of the invention are attained by providing a sewing machine with an attachment having means to engage a stitched material and feed or advance the same as the sewing operation progresses and at a speed substantially the same as that of the material being fed through the sewing machine. The feeding or advancing means comprises rotary means positioned to engage the stitched material on the base of the sewing machine head, table or work support (all herein called work support) after the sewing operation and which cooperate with the work support to feed or advance the stitched material over the work support. In one embodiment of the invention, wherein two pieces of material are joined together by a seam and the two pieces extend in opposite directions from the seam, a rotary means is positioned to engage the stitched material on the seam thereof and one or more rotary means are positioned and dis-

posed in spaced relationship and to the right or to the left, or both to the right and left, of the rotary means engaging the seam, depending on the relative widths of the two materials joined together by the seam.

The nature of the rotary devices cooperating with the work support and feeding the stitched material depends on the nature of the fabric which has been seamed together. In general, the rotary means engaging the seam comprises a roll formed of any suitable material and provided with a tractive surface. A suitably ribbed, fluted or etched roll, a wooden roll, a cork roll, and a leather-surfaced roll are illustrative examples of seam-engaging rolls which give satisfactory results. Similar rolls may constitute the other rotary means which cooperate with the work support and engage the stitched material at places spaced from the seam. In the preferred embodiment of the invention, ribbed rolls in which the ribs are convex and formed of a resilient and yielding composition, such as rubber, leather, etc., constitute the rotary means engaging the material to the right or left, or both to the right and left, of the seam. Such a ribbed roll is formed by compressing a tube of selected material having its wall provided with spaced (preferably equally spaced) slits. Due to the compression, the strips are bulged outwardly forming spaced convex ribs and constitute a highly satisfactory yielding tractive surface. Means are provided to control and adjust the degree of compression whereby the strips are bulged outwardly to a greater or lesser degree depending on the desired grip thereof on the goods.

The aforementioned rolls are, as previously mentioned, disposed beyond the needle at the rear of the machine and cooperate with the work support of the machine in the feeding operations. The rolls are mounted in the desired spaced positions on a shaft driven from the needle drive shaft. The driving means is located at the pulley end of the machine. In operation, the peripheral speed of the rolls is substantially the same as the linear speed at which the material is fed through the sewing position, although, of course, this can be varied as desired.

When the machine and attachment are employed during the joining of relatively light materials, such as silk, rayon or the like, or any material which might tend to cling and wind around the rolls, strippers are provided to cooperate with each roll and thereby inhibit the clinging or winding up of the material on the roll and permit continuous advancing of the stitched material.

The attachment is also so designed and constructed that it can be adjusted into inoperative position in the event it is desired not to wholly remove the attachment.

The invention is equally applicable to a single

or multiple needle machine and the seam joining the two pieces of material may be of any type. In the event the type of seam is that which requires a folder or some other mechanism to dispose the material in proper position for stitching, such mechanism can be positioned in advance of the needles. Highly satisfactory results have been obtained when two pieces of relatively wide material, such as used in the manufacture of parachutes, were joined by a tailored French seam with the raw edges concealed and stitched with two parallel rows of stitches extending longitudinally of the seam and passing through all the plies in the seam.

The nature of the invention will become clearer from the description of the illustrative embodiment thereof shown in the drawings, and wherein:

Figure 1 is a top plan view, partly cut away for clarity, of a sewing machine head with the attachment positioned in place;

Figure 2 is an end view of the sewing machine and attachment, and partly in section, as viewed from the left of Figure 1;

Figure 3 is an end view of the sewing machine and attachment as viewed from the right of Figure 1;

Figure 4 is a section taken on the line 4—4 of Figure 1;

Figure 5 is a partial end view of a tailored French seam joining two pieces of fabric;

Figure 6 is a perspective view of the support of the attachment;

Figure 7 is a longitudinal section of the rotary device engaging the stitched material to the right of the needles; and

Figure 8 is a longitudinal section of the rotary device engaging the stitched material to the left of the needles.

Referring now to the drawings, wherein like reference numerals designate like parts, the reference numeral 10 designates a known sewing machine head having a base 12 and a needle bar 14 which carries a needle carrier 15 carrying two needles 16. The sewing machine head is also provided with a presser foot bar 18, which carries a presser foot 20 designed to cooperate with feed dogs 22 which pass through slots 24 of a removable cover plate 26. The cover plate 26 is also provided with apertures (not shown) which permit the penetration of the needles during the sewing operation. A manually actuated lever 30 for elevating or lowering the presser foot bar is also provided. The reciprocating needle bar 14 is driven through a shaft (not shown) by a pulley 32. A belt 34 driven from a well-known means (not shown) drives the pulley 32. Adjacent the pulley end of the machine there is provided a knurled head 36.

The sewing machine head, described immediately before, is of the standard, well-known two-needle type.

In the illustrative embodiment of the invention to be hereafter described, two pieces of material 37 and 38 are joined together by a tailored French seam 39, with the two pieces of material extending in opposite directions from the seam, as shown in Figure 5. With this in view, a folder 40 is adjustably and removably secured to the base 12 of the machine by screws 42. The folder 40 is of the type which, when the two edges of the material 37 and 38 are fed therethrough, will roll the edges thereof to form the seam 39, in which the folded portions are interlocked and the raw edges concealed, and deliver the seam to the

needles for stitching, thereby producing a stitched seam of the type shown in Figure 5. Since the details of the folder form no essential part of this invention, further discussion thereof is unnecessary.

The material 37 and 38, folded by the folder 40 to provide the tailored French seam 39 as previously mentioned, is fed through the stitching position beneath the needles 16, whereby the seam 39 is stitched by two parallel rows of stitching 44. As shown in Figure 5, the two rows of stitching penetrate all the plies constituting the seam 39 and are visible on both sides of the seam. The folder 40 is provided adjacent its exit end with a tongue 46 to aid in presenting the seam 39 in proper position and condition for stitching by the needles.

The attachment which constitutes one phase of the invention, and as shown in Figure 1, is positioned on or adjacent the rear of the base 12. The attachment includes a cork roll 50 which is positioned above, but in cooperative relationship with, the work support and beyond (to the rear) of the stitching position to engage at least the seam 39 after it has passed through the stitching position and while on the work support. The roll 50 is securely and preferably also adjustably mounted on a sleeve 52 which encases and is secured, by a screw 53, to a shaft 54 which, as shown in the drawing, is disposed above the work support at the rear of the head 10 and driven, as hereinafter described, from the pulley 32.

In one embodiment of the invention, the attachment is also provided with a rotary member 56 spaced from and to the right of the roll 50, as viewed in Figure 1.

Referring now to Figure 7, the rotary member 56 comprises a tube 58 of soft rubber which is slit longitudinally and intermediate its ends to provide a plurality of strips or ribs 60. One end 62 of the rubber tubing (which, as is apparent from the drawings, is not slit) is secured to an enlargement 64 of a sleeve 66 formed of a hard material, such as vulcanized rubber. The other end 70 of the slit tube 58 (which also is not slit) is secured to a sleeve 74, also formed of a hard material, such as vulcanized rubber, and having an enlargement 76 against which the end 70 of the tubing abuts. The sleeve 74 is slidably mounted on the sleeve 66 and is locked thereto, after adjustment to the desired position, by the set screw 78. The sleeve 66 is secured to the sleeve 52, which is secured to the shaft 54, by means of a screw 80. For reasons which will become apparent hereafter, the sleeve 52 does not extend through the entire length of the sleeve 66 but only through a portion thereof, as shown in Figure 7.

After the rotary member 56 is positioned on the sleeve 52 and secured thereto by means of the set screw 80, the sleeve 74 is then slidably moved on the sleeve 66 in a direction to longitudinally compress the rubber tubing 58 so that the strips 60 thereof will be bulged outwardly to form spaced convex ribs. Depending on the position of the sleeve 74 relative to the sleeve 66, the ribs 60 may be bulged to a greater or lesser degree, the degree depending on the nature of the material to be engaged thereby. When the desired convexity of the strips 60 has been secured by the adjustment of the sleeve 74, the sleeve 74 is locked and secured to the sleeve 66 by means of the set screw 78.

The shaft 54, as previously mentioned, is disposed rearwardly of the head 10 and driven from

the pulley end of the machine. In the form shown, a pulley 86 is secured to the pulley 32 in any suitable manner. The pulley 86 drives a belt 88 formed of an elastic material, such as rubber, and cooperates with a pulley 90 carried on one end of a shaft 92 positioned rearwardly of the head. As shown in Figures 1 and 6, the shaft 92 is journaled in an arm 94 of a bifurcated block 96 mounted at the rear of the sewing machine head. The other end of the shaft 92 is journaled in the other arm 98 of the block 96. Adjacent the arm 98, the shaft 92 is provided with a gear 100 which meshes with a gear 102 mounted on a stud shaft 104 carried by the arm 98. A gear 106 on the stud shaft 104 meshes with a gear 108 carried on the end of the shaft 54 and journaled in the arm 98. From the description, it is clear that the arm 98 constitutes a bearing for the shaft 54 and the gears 100, 102, 106 and 108 serve as a reducing gear train, and, by proper selection of the gears, any appropriate speed may be imparted to the shaft 54. If desired, the arm 98 and the gear train may be encased in a cover (not shown). It will thus be seen that, when the machine is operated, the shaft 54 will be operated and the roll 50 and the rotary member 56 will be driven as the stitching operation progresses.

The block 96 is provided with depending lugs 110 and 112 through which a pivot shaft 114 extends. The opposite ends of the shaft 114 are secured in ears 118 of the arms 121 and 122 of a base 123. The base 123 is secured to the work support by means of screws 124 passing through apertures 124 and cooperating with the horizontal member 125 thereof. The horizontal member 125 of the base 123 is provided with a pair of leveling screws 126 whereby the attachment may be adjusted to proper horizontal position. As shown in Figure 4, each of the leveling screws 126 is provided at its lower end with a washer 128 loosely swedged to the shank of the screw 126 and disposed intermediate the base 123 and the work support. Thus, by raising or lowering the screws 126, the base 123 may be raised or lowered at either or both ends thereof as desired.

In order to maintain the block 96 so that it will carry the other pertinent elements and maintain the roll 50 and rotary device 56 in operative position with respect to the work support, the pivot shaft 114 is provided with a spring 130 secured between two collars 132 and 134. As is shown in Figure 6, one end of the spring 130 is secured to the collar 132 and the other end thereof is secured to the block 96 as at 136.

The spring 130 through its connection to the block 96, exerts a force thereon so that the block 96 will be urged downwardly and the feeding devices positioned in cooperative relationship with the work support. The ends of the shaft 114 may be locked in position in the ears 118 by suitable means, such as set screws.

When it is desired to raise the roll 50 and rotary device 56 from operative position to inoperative position, the block 96 is moved so that the necessary pivotal movement on the shaft 114 may be secured. In order to maintain the attachment in inoperative position, there is provided the spring 140, the upper end 142 being curved and adapted to engage a horizontal member 97 of the block 96 and hold it in position. The other end of the spring 140 is secured by means of screws 144 to the base 123.

In another embodiment of the invention, there is provided a rotary member 150 spaced and to

the left of the roll 50, as viewed in Figure 1. The rotary member 150 comprises a tube 152 formed of a flexible and yielding material, such as soft rubber, and which is slit longitudinally and intermediate its ends to provide a plurality of ribs 154. One end of the slit rubber tubing 152 (which has not been slit) is secured to a sleeve 156 which is adjustably secured by means of a set screw 158 to the sleeve 52. Alternatively, the sleeve 156 may, as shown in Figure 1, be provided with a collar and the collar secured to the sleeve. The other end of the rubber tubing 152 (which has not been slit) is secured to a sleeve 160 which is slidably positioned on the sleeve 52. The sleeve 52 is provided with a key 162 which cooperates with a key slot in both sleeves 156 and 160. An adjusting screw 164 cooperating with the sleeve 160 permits adjustable positioning of the sleeve 160 longitudinally on the sleeve 52 with respect to the sleeve 156. By rotating the adjusting screw 164 in the desired direction, the tube 152 is longitudinally compressed and the strips 154 bulge outwardly to provide convex ribs. The extent and degree of the bulge is adjustable by means of the screw 164, and the desired extent and degree depend on the nature of the material to be engaged thereby. A spring 166, cooperating with the sleeve 160 and the adjusting screw 164, prevents accidental movement of the screw 164 whereby it will maintain its adjusted position.

Some materials engaged by the roll 50 and the rotary devices 56 and 150 have a tendency to cling to, and in some instances indeed wrap around, said members. In order to avoid this, means are provided to cooperate with the roll 50, the rotary member 56, and the second rotary member 150, to prevent the clinging, or indeed the wrapping around, of the fabric on the respective member. With this in view, the roll 50 is provided with a plurality of grooves 170 which cooperate with fingers 172 respectively carried by a head 174 loosely and pivotally mounted on a shaft 176. The rotary device 56, and particularly the enlargements 68 and 76 of the sleeves 66 and 74, are provided with grooves 178 and 180 respectively. A stripper finger 182 cooperates with the groove 178 and is adjustably mounted on the shaft 176. It is secured in place on the shaft 176 by means of a set screw 184. A finger 186 cooperates with the groove 180 and it is loosely mounted on the shaft 176. The finger 186 is secured to one end of a spring 188, the other end of which is slidably disposed in an ear carried by the finger 182. Thus, it will be seen that, when the sleeve 74 is adjusted with respect to the sleeve 66, the finger 186 will slide with said sleeve in the adjustment thereof while the finger 182 remains stationary.

The sleeves 156 and 160 respectively of the rotary member 150 are likewise provided with grooves 190 and 192 respectively. Stripper fingers 194 and 196 cooperate with the grooves 190 and 192 respectively. The stripper finger 194 is loosely mounted on the shaft 176 and the stripper finger 196 is secured to the shaft 176 by means of a set screw 198. One end of a spring 200 is secured to the finger 194, the other end being slidably disposed in a hole of the stripper finger 196. The stripper fingers 194 and 196 and their mounting thereof on the shaft 176 to provide relative movement therebetween and the adjustment of the sleeve 160 are identical with the arrangement of the comparable elements with respect to the rotary device 56.

One end of the shaft 176 is secured in a bracket 210 by means of a screw 212. The other end of the bracket 210 is provided with a boss 214 which is secured by means of a screw 216 to a stationary sleeve 218 which, as shown in Figure 7, extends adjacent the arm 94 to the interior of the rotary member 56 and terminates in spaced relationship to the sleeve 52. In the form shown in Figure 1, the boss 214 of the bracket 210 is positioned adjacent the arm 98 and the sleeve 66.

From the foregoing description, it is apparent that the attachment contemplates the seam-engaging roll 50 with or without the rotary device 56, and with or without the rotary device 150, as desired. The peripheral speed of the roll 50 is substantially equal to the speed of the material passing through the stitching position, and the peripheral speeds of the rotary devices 56 and 150 are substantially the same as those of the roll 50 though they may be higher or lower and yet accomplish the intended functions.

It is further to be noted that when the block 96 is moved with respect to the base 123 to render the roll 50 and also the other rotary devices when used ineffective, the entire attachment (except for the base 123) is moved. By making the belt 88 of a yielding elastic material, it need not be removed when the attachment is moved to inoperative position. When it is desired to entirely remove the attachment, the screws 124 are removed and the base 123, together with all the elements carried thereby, are removed from the machine.

Since it is obvious that various changes and modifications may be made in the above description without departing from the nature or spirit thereof, this invention is not restricted thereto except as set forth in the appended claims.

I claim:

1. A sewing machine having a work support, a head, a reciprocating needle bar carrying one or more needles, means to reciprocate said needle bar including a driving shaft and a pulley in driving relationship to said driving shaft, said pulley and needle bar being on opposite ends of said head, means to feed two pieces of material in position for stitching by said needles to form a seam with the two pieces of material extending in opposite directions from said seam, a shaft disposed above the work support and to the rear of said head provided with a roll to engage the stitched material at the seam, a ribbed roll positioned on said shaft laterally of and spaced from the seam-engaging roll to engage the stitched material, the ribs of said ribbed roll being yieldable, and means driven by the pulley to drive said shaft to actuate said roll and ribbed roll.

2. A sewing machine having a work support, a head, a reciprocating needle bar carrying one or more needles, means to reciprocate said needle bar including a driving shaft and a pulley in driving relationship to said driving shaft, said pulley and needle bar being on opposite ends of said head, means to feed two pieces of material in position for stitching by said needles to form a seam with the two pieces of material extending in opposite directions from said seam, a shaft disposed above the work support and to the rear of said head provided with a pair of ribbed rolls to engage the stitched material on opposite sides of the seam, a roll on said shaft spaced from and intermediate said ribbed rolls to engage the stitched material at the seam thereof, the ribs of said ribbed rolls being yieldable, and means driven

by the pulley to drive said shaft and simultaneously drive all of said rolls.

3. A sewing machine having a work support, a head, a reciprocating needle bar carrying one or more needles, means to reciprocate said needle bar including a driving shaft and a pulley in driving relationship to said driving shaft, said pulley and needle bar being on opposite ends of said head, means to feed two pieces of material in position for stitching by said needles to form a seam with the two pieces of material extending in opposite directions from said seam, a shaft disposed above the work support and to the rear of said head provided with a feed roll to engage the stitched material at the seam, a rotary feed device positioned on said shaft laterally of and spaced from the seam-engaging roll to engage the stitched material, means driven by the pulley to drive said shaft to actuate said roll and rotary feed device, strippers cooperating with said roll and rotary feed device, a stationary shaft, and means to adjustably position said strippers on said stationary shaft.

4. A sewing machine having a work support, a head, a reciprocating needle bar carrying one or more needles, means to reciprocate said needle bar including a driving shaft and a pulley in driving relationship to said driving shaft, said pulley and needle bar being on opposite ends of said head, means to feed two pieces of material in position for stitching by said needles to form a seam with the two pieces of material extending in opposite directions from said seam, a shaft disposed above the work support and to the rear of said head provided with a feed roll to engage the stitched material at the seam, a pair of rotary feed devices, one on each side of and spaced from the seam-engaging roll to engage the stitched material, means driven by the pulley to drive said shaft to actuate said roll and rotary feed devices, strippers cooperating with said roll and rotary feed devices, a stationary shaft, and means to adjustably position said strippers on said stationary shaft.

5. A sewing machine having a work support, a head, a reciprocating needle bar carrying one or more needles, means to reciprocate said needle bar including a driving shaft and a pulley in driving relationship to said driving shaft, said pulley and needle bar being on opposite ends of said head, means to feed two pieces of material in position for stitching by said needles to form a seam with the two pieces of material extending in opposite directions from said seam, a shaft disposed above the work support and to the rear of said head provided with a roll to engage the stitched material at the seam and a ribbed roll positioned laterally of and spaced from the seam-engaging roll to engage the stitched material, means driven by the pulley to drive said shaft to actuate said roll and ribbed roll, a stripper cooperating with each of said rolls, a stationary shaft, and means to adjustably position said strippers on said stationary shaft.

6. A sewing machine having a work support, a head, a reciprocating needle bar carrying one or more needles, means to reciprocate said needle bar including a driving shaft and a pulley in driving relationship to said driving shaft, said pulley and needle bar being on opposite ends of said head, means to feed two pieces of material in position for stitching by said needles to form a seam with the two pieces of material extending in opposite directions from said seam, a shaft disposed above the work support and to the rear

of said head provided with a pair of ribbed rolls to engage the stitched material on opposite sides of the seam and a roll spaced from and intermediate said ribbed rolls to engage the stitched material at the seam thereof, means driven by the pulley to drive said shaft and simultaneously drive all of said rolls, a stripper cooperating with each of said rolls, a stationary shaft, and means to adjustably position said strippers on said stationary shaft.

7. A sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, a roll cooperating with the work support to engage the stitched material at the seam, a ribbed roll cooperating with the work support and positioned laterally of and spaced from the seam-engaging roll to engage the stitched material, and means driven by the pulley to drive said roll and ribbed roll to feed the stitched material, said ribbed roll comprising a tubing formed of a yielding material and provided with slits extending longitudinally of the tubing and intermediate the ends thereof, and adjustable means to compress said tubing to form convex ribs.

8. A sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, a roll cooperating with the work support to engage the stitched material at the seam, a ribbed roll cooperating with the work support and positioned laterally of and spaced from the seam-engaging roll to engage the stitched material, and means driven by the pulley to drive said roll and ribbed roll to feed the stitched material, said ribbed roll comprising a tubing formed of a yielding material and provided with slits extending longitudinally of the tubing and intermediate the ends thereof, a pair of sleeves, each end of said tubing being secured to the respective sleeve, and means to move said sleeves relative to each other in a direction parallel to the longitudinal axis of said tubing to compress said tubing.

9. A sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, a roll cooperating with the work support to engage the stitched material at the seam, a ribbed roll cooperating with the work support and positioned laterally of and spaced from the seam-engaging roll to engage the stitched material, and means driven by the pulley to drive said roll and ribbed roll to feed the stitched material, said ribbed roll comprising a tubing formed of a yielding material and provided with slits extending longitudinally of the

tubing and intermediate the ends thereof, a sleeve, a second sleeve slidably disposed on the first-named sleeve, one end of said tubing being secured to the first-named sleeve and the other end of the tubing being secured to the second sleeve, and means to secure said sleeves together, said sleeves being disposed relative to each other to longitudinally compress said tubing.

10. A sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, a shaft at the rear of the machine head, a roll mounted on said shaft and cooperating with the work support to engage the stitched material at the seam, a ribbed roll mounted on said shaft positioned in cooperative relationship with the work support laterally of and spaced from the seam-engaging roll to engage the stitched material, means driven by the pulley to drive said shaft, said ribbed roll comprising a tubing formed of a yielding material and provided with slits extending longitudinally of the tubing and intermediate the ends thereof, a sleeve secured to said shaft, a second sleeve slidably mounted on the first-named sleeve, one end of said tubing being secured to the first-named sleeve, the other end of the tubing being secured to the second sleeve, means to lock the second sleeve to the first-named sleeve, said sleeves being disposed relative to each other to longitudinally compress said tubing.

11. A sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, a shaft at the rear of the machine head, a roll mounted on said shaft and cooperating with the work support to engage the stitched material at the seam, a ribbed roll mounted on said shaft positioned in cooperative relationship with the work support laterally of and spaced from the seam-engaging roll to engage the stitched material, and means driven by the pulley to drive said shaft, said ribbed roll comprising a tubing formed of a yielding material and provided with slits extending longitudinally of the tubing and intermediate the ends thereof, a pair of sleeves disposed on said shaft and driven thereby, each end of said tubing being secured to the respective sleeve, and means to slidably move one of said sleeves relative to each other in a direction parallel to the longitudinal axis of said tubing to compress said tubing.

12. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, said attachment to be mounted to the rear of

said head and comprising a base to be secured to the work support, a shaft carried by said base and to be disposed above the work support and to the rear of said head, means driven from said pulley to drive said shaft, a roll on said shaft to cooperate with the work support and engage the stitched material at the seam thereof, a ribbed roll on said shaft laterally of and spaced from said seam-engaging roll to engage the stitched material, the ribs of said ribbed roll being yieldable, and means to position and move said shaft and rolls to operative or inoperative position.

13. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, said attachment to be mounted to the rear of said head and comprising a base to be secured to the work support, a shaft carried by said base and to be disposed above the work support and to the rear of said head, means driven from said pulley to drive said shaft, a roll on said shaft to cooperate with the work support and engage the stitched material at the seam thereof, a pair of ribbed rolls mounted on said shaft to engage the stitched material, the seam-engaging roll being disposed intermediate said rolls and laterally spaced therefrom, the ribs of said ribbed rolls being yieldable, and means to position and move said shaft and rolls to operative or inoperative position.

14. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, said attachment to be mounted to the rear of said head and comprising a base to be secured to the work support, a bearing pivotally mounted on said base, a shaft in said bearing and to be disposed above the work support and to the rear of said head, means driven from said pulley to drive said shaft, a roll on said shaft to cooperate with the work support and engage the stitched material at the seam thereof, a ribbed roll on said shaft and positioned laterally of and spaced from the seam-engaging roll to cooperate with the work support and engage the stitched material, a stripper to cooperate with each of said rolls, a stationary shaft, means to adjustably position said stripper on said stationary shaft, and means to maintain said bearing in position to dispose said shaft and rolls in operative or inoperative position.

15. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, said at-

tachment to be mounted to the rear of said head and comprising a base to be secured to the work support, a bearing pivotally mounted on said base, a shaft in said bearing and to be disposed above the work support and to the rear of said head, means driven from said pulley to drive said shaft, a roll on said shaft to cooperate with the work support and engage the stitched material at the seam thereof, a pair of ribbed rolls on said shaft to cooperate with the work support and engage the stitched material, the seam-engaging roll being disposed intermediate the ribbed rolls and laterally spaced therefrom, a stripper to cooperate with each of said rolls, a stationary shaft, means to adjustably position said stripper on said stationary shaft, and means to maintain said bearing in position to dispose said shaft and rolls in operative or inoperative position.

16. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, said attachment to be mounted to the rear of said head and comprising a base to be secured to the work support, a block pivotally mounted on said base, a shaft carried by said block, means driven from said pulley to drive said shaft, a second shaft driven by the first shaft, a roll on said second shaft to cooperate with the work support and engage the stitched material at the seam thereof, and means to maintain said block in position to dispose said second shaft and roll in operative or inoperative position.

17. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed two pieces of material in position for stitching by said needles to form a seam with the two pieces of material extending in opposite directions from said seam, said attachment to be mounted to the rear of said head and comprising a base to be secured to the work support, a block pivotally mounted on said base, a shaft carried by said block, means driven from said pulley to drive said shaft, a second shaft driven by the first shaft, a roll on said second shaft to cooperate with the work support and engage the stitched material at the seam thereof, a ribbed roll on said shaft and positioned laterally of and spaced from the seam-engaging roll, the ribs of said ribbed roll being yieldable, and means to maintain said block in position to dispose said shaft and rolls in operative or inoperative position.

18. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed material in position for stitching by said needles, said attachment comprising a shaft to be disposed rearwardly of the head, means driven by said pulley to drive said shaft, and a ribbed roll on said shaft to cooperate with the work support and engage the stitched material laterally and spaced

from the stitched portion thereof, said ribbed roll comprising a tubing formed of a yielding material and provided with slits extending longitudinally of the tubing and intermediate the ends thereof, and adjustable means to compress said tubing to form convex ribs.

19. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed material in position for stitching by said needles, said attachment comprising a shaft to be disposed rearwardly of the head, means driven by said pulley to drive said shaft, and a ribbed roll on said shaft to cooperate with the work support and engage the stitched material laterally and spaced from the stitched portion thereof, said ribbed roll comprising a tubing formed of a yielding material and provided with slits extending longitudinally of the tubing and intermediate the ends thereof, a pair of sleeves, each end of said tubing being secured to the respective sleeves, and means to permit movement of said sleeves relative to each other in a direction parallel to the longitudinal axis of said tubing to compress said tubing.

20. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed material in position for stitching by said needles, said attachment comprising a shaft to be disposed rearwardly of the head, means driven by said pulley to drive said shaft, and a ribbed roll on said shaft to cooperate with the work support and engage the stitched material laterally and spaced from the stitched portion thereof, said ribbed roll comprising a tubing formed of a yielding material and provided with slits extending longitudinally of the tubing and intermediate the ends thereof, a sleeve to be disposed on and secured to said shaft, a second sleeve slidably disposed on the first-named sleeve, one end of said tubing being secured to the first-named sleeve, the other end of said tubing being secured to the second sleeve, and means to secure said sleeves together, said sleeves being disposed relative to each other to longitudinally compress said tubing.

21. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed material in position for stitching by said needles, said attachment comprising a shaft to be disposed rearwardly of the head, means driven by said pulley to drive said shaft, and a ribbed roll on said shaft to cooperate with the work support and engage the stitched material laterally and spaced from the stitched portion thereof, said ribbed roll comprising a tubing formed of a yielding material and provided with slits extending longitudinally of the tubing and intermediate the ends thereof, a pair of sleeves disposed on said shaft and driven thereby, each end of said tubing being secured

to the respective sleeve, and means to slidably move one of said sleeves on said shaft relative to the other in a direction parallel to the longitudinal axis of said tubing to compress said tubing.

5 22. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed material in position for stitching by said needles, said attachment comprising a shaft to be disposed rearwardly of the head, means driven by said pulley to drive said shaft, and a ribbed roll on said shaft to cooperate with the work support and engage the stitched material laterally and spaced from the stitched portion thereof, said ribbed roll comprising a tubing formed of a yielding material and provided with slits extending longitudinally of the tubing and intermediate the ends thereof, a sleeve to be disposed on and secured to said shaft, a second sleeve slidably disposed on the first-named sleeve, one end of said tubing being secured to the first-named sleeve, the other end of said tubing being secured to the second sleeve, and means to secure said sleeves together, said sleeves being disposed relative to each other to longitudinally compress said tubing, each of said sleeves being provided with a groove adjacent the end thereof, stripper fingers cooperating with each groove, a stationary shaft carrying said fingers, the finger cooperating with the sleeve being secured to the rotating shaft and the finger cooperating with the other sleeve being slidably disposed on said shaft whereby upon adjustment of the slideable sleeve the slideable finger will also be adjusted.

30 23. An attachment for a sewing machine having a work support, a head, a reciprocating needle bar carrying one or more needles, means to reciprocate said needle bar including a driving shaft and a pulley in driving relationship to said shaft, said pulley and needle bar being on opposite ends of said head, means to feed material in position for stitching by said needles, said attachment comprising a shaft to be disposed rearwardly of the head, means driven by said pulley to drive said shaft, and a ribbed roll on said shaft to cooperate with the work support and engage the stitched material laterally and spaced from the stitched portion thereof, said ribbed roll comprising a tubing formed of a yielding material and provided with slits extending longitudinally of the tubing and intermediate the ends thereof, a pair of sleeves disposed on said shaft and driven thereby, one of said sleeves being secured to the shaft, each end of said tubing being secured to the respective sleeve, and means to slidably move one of said sleeves on said shaft relative to the other in a direction parallel to the longitudinal axis of said tubing to compress said tubing, each of said sleeves being provided with a groove adjacent the end thereof, stripper fingers cooperating with each groove, a stationary shaft carrying said fingers, the finger cooperating with the sleeve being secured to the rotating shaft and the finger cooperating with the other sleeve being slidably disposed on said shaft whereby upon adjustment of the slideable sleeve the slideable finger will also be adjusted.

CHARLES SEAMAN.
